UNITED STATES PATENT OFFICE.

JOHN L. SOMMER AND THOMAS HARDING, OF NEWARK, NEW JERSEY, ASSIGNEES TO
J. L. SOMMER MANUFACTURING CO., A CORPORATION OF NEW JERSEY.

DESIGN FOR A CAKE-TURNER OR SIMILAR KITCHEN UTENSIL.

53,054.

Specification for Design.

Patented Mar. 4, 1919.

Application filed October 5, 1917. Serial No. 194,995. Term of patent 14 years.

To all whom it may concern:

Be it known that we, JOHN L. SOMMER and THOMAS HARDING, both citizens of the United States, residing at Newark, in the county of Essex and State of New Jersey, have invented a new, original, and ornamental Design for a Cake-Turner or Similar Kitchen Utensil, of which the following is a specification, reference being had to the accompanying drawing, forming part thereof.

Figure 1 is a side view of a cake turner showing our new design, and

Fig. 2 is an edge view of the same.

We claim:

The ornamental design for a cake turner or similar kitchen utensil, as shown.

JOHN L. SOMMER.
THOMAS HARDING.
